UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

SHANK AND BIT PUNCH.

Application filed August 20, 1925. Serial No. 51,363.

This invention relates to shank and bit punches for opening the bores of hollow articles as for instance drill steels, and the invention is applied to both the push punch and the hammer punch type of machine. In the push punch type the punch pin is pushed or forced into the drill steel by steady pressure applied mechanically or by pressure fluid means and pulled out by the same means, while in the hammer type punch the pin is hammered into the drill steel by blows in one direction and hammered out of the drill steel by blows in the opposite direction. These blows in opposite directions may be repeatedly applied or one blow may be sufficient to drive the pin into the steel and another blow may be sufficient to drive the pin out of the steel, the number of blows depending upon the resistance to the entry or withdrawal of the pin.

The objects of the invention are to simplify the construction of such machines and in the case of the hammer punch secure a simple and efficient feeding device for feeding the pin punch forwardly and withdrawing it rearwardly while the hammer is in action.

The invention is shown in some of its preferred forms in the accompanying drawings, in which—

Figure 1 is a side elevation partly in longitudinal section of a machine,

Figure 2 is a similar view showing a modification, and

Figure 3 is a similar view showing the hammer punch type of machine having an air feed.

Referring to the drawings which are diagrammatic, the base A which may be the base of a drill sharpener or a bracket attached thereto or a separate pedestal, has provided in connection therewith the clamping jaws B for holding the drill steel E. This machine may be mounted at the side of a drill sharpener as illustrated in U. S. Patent No. 1,304,459 granted May 20, 1919, to Jesse Ditson for drill sharpener, which patent illustrates the use of a pin punch on a sharpener and shows the punch mounted on a bracket on one side of the axis of the main jaws of the sharpener, supplemental jaws being provided at one side of the sharpener for holding the drill steel and these supplemental jaws may be the jaws B

indicated in the drawings of this application.

On the frame or bracket A is provided the casing F containing a suitable reversible motor of any suitable type, in this instance shown as a fluid actuated gear motor comprising the gears G and H for actuating the pin punch J forwardly and rearwardly.

The pin J is mounted in a suitable carriage shown in this instance in the form of a rack K movable longitudinally in the guides L and O and having a socket P in which the punch pin J is held by the key or pin Q. A pinion R connected to the shaft S of the gear H, engages the teeth of the rack K and as the pinion R is rotated in opposite directions according to the direction of rotation of the gear H, the rack K will be carried rearwardly and forwardly to force the pin J into the drill steel and out of the drill steel.

Motive fluid for operating the motor is supplied through the bore of the valve T controlled by the handle U and in the position of the parts indicated in Figure 1 pressure fluid passes the passage V to the motor casing and drives the gears G and H in the direction indicated by the arrows so that the pinion R is driven counter-clockwise and the punch pin is carried into the drill steel. By reversing the valve T pressure fluid enters the motor casing through the inlet port X and the direction of the motor is reversed to withdraw the punch from the steel. The motor casing is provided with exhaust ports Y which function for either direction of rotation of the motor. With this apparatus the punch pin is quickly and forcibly pushed or carried into the drill steel and quickly withdrawn by manipulation of the valve lever U.

In the modification shown in Figure 2, the construction of the motor is similar to that indicated in Figure 1 but instead of a rack bar, a screw Z is provided for carrying the pin J, and a worm *a* on the shaft S of the gear H meshes with the worm gear *b* mounted in the casing F. The worm gear *b* has an internal gear engaging the screw bar Z and a key *c* in the guide O' engages a longitudinal slot *d* in the screw bar Z, so that rotation of the worm gear *b* in one direction or the other carries the screw Z longitudinally forwardly or rearwardly and

the pin J is forced into and out of the drill steel.

In the modification shown in Figure 3, the frame A is provided with a guide bar e 5 on which slides a casing f to which is connected a hammer punch g like that illustrated in U. S. Patent No. 1,463,134 granted July 24, 1923 to Harry V. Haight for shank and bit punch, or else some other suitable 10 type of hammer punch may be provided. The anvil block P' carrying the punch pin J receives blows of impact in one direction or another to hammer the pin into the drill steel and hammer the pin out of the drill 15 steel as disclosed in said Haight patent.

For feeding the hammer punch forwardly and rearwardly a suitable reversible motor is provided in the casing h, in this instance a 20 pressure fluid motor of the gear type being illustrated like that shown in the other figures. The pinion R connected to the shaft S' with the gear G engages a rack j having a reduced shank k passing through the boss o on the casing f. A nut p and lock nut q 25 on the shank k permit a given amount of play between the boss o and the collar r and nut p. Pressure fluid for actuating the motor in the casing h is controlled by a suitable 30 valve (not shown) actuated by the handle s and pressure fluid for actuating the hammer of the hammer punch is admitted through the connection t and if desired, the supply of pressure fluid to the hammer punch may be controlled by the same valve and handle 35 s which controls the supply of fluid to the motor.

In the operation of the device shown in Figure 3, the rack j is forced forwardly when the motor rotates in one direction to feed the hammer punch forwardly while the 40 hammer is in action. Upon reversing the gear motor the rack j is carried rearwardly and owing to the lost motion connection between the shank k and the boss o, the motor may attain maximum speed before its 45 force is applied to the hammer punch, so that a sharp blow is given to the boss and casing f by the nut p in order to start the withdrawal of the pin J from the drill steel, it being understood that the hammer 50 remains in action to hammer the pin out of the drill steel while the hammer punch is being withdrawn.

I claim:

In a shank and bit punch, the combination of means for clamping a drill steel, a hammer punch having a pin adapted to be hammered into the drill steel and hammered out of the drill steel, a base, a fluid actuated reversible motor secured fixedly on said base, and operative connections including a rack connected at one end to the hammer punch and a gear carried by the motor to mesh with the rack for moving the hammer punch forwardly and rearwardly while the hammer is in action, said operative connections including a lost motion connection between the motor and the hammer punch. 55

In testimony whereof I have signed this specification.

FRED M. SLATER.
